DIRECTION FINDER

Laurens A. Taylor, Schenectady, N. Y., assignor to
General Electric Company, a corporation of
New York

Application January 27, 1934, Serial No. 708,650

5 Claims. (Cl. 250—11)

My invention relates to receiving systems and more particularly to systems used for direction finding, radio course indicating, and the like.

A substantially instantaneously responsive non-linear resistor is described in United States Patent No. 1,822,742 issued to K. B. McEachron, and is commercially known as "Thyrite." This non-linear resistor has a hyperbolic resistance-current characteristic which can be expressed in the form of a simple hyperbolic equation as $R=CI^{-a}$, where R is the resistance I is the density of the current in amperes, C is a constant and the exponent a is the slope of the curve represented by the equation when plotted with respect to logarithmic coordinates. The exponent a is less than unity and the constant C is between the ranges of 10 and 600. This material has the peculiar property of reacting substantially instantaneously to asymmetrical voltage or current wave shapes so that a portion of such waves is rectified and a direct current impulse flows in the circuit; but when symmetrical waves are passed through it, no direct current flow occurs. The direction of the direct current flow due to the partial rectification of asymmetrical wave shapes is dependent upon whether the maximum peak of the asymmetrical wave is of positive or negative value.

In radio direction finders in the past it has been common to utilize a loop or directive antenna so that the minimum effect of the antenna indicates the direction of the radio transmitter. In such systems the minimum effect is not particularly well defined and it has been found that radio direction finders which do not work on the loop antenna minimum are much more efficient receiving devices and are capable of indicating the direction of the radio transmitter with greater accuracy. A system of the latter type utilizes a directive antenna having a certain amount of the so-called vertical effect which distorts the normal figure 8 pattern of the loop antenna so as to produce a field intensity pattern of one of the various cardioid configurations. It is further desirable in direction finders to provide such receiving systems which do not require any balancing devices to secure any relative balance of circuits or currents.

In accordance with my invention, it has been found that by utilizing a directive antenna having a certain amount of vertical effect and an arrangement for symmetrically or sinusoidally reversing the phase of the energy collected by the antenna and impressed upon a radio receiver, a simple output circuit utilizing a non-linear re-

sistor such as "Thyrite" acts as an extremely economical and reliable direction finder.

It is therefore an object of my invention to provide an improved economical direction finder which does not depend upon the loop antenna minimum effect. 5

The novel features which I believe to be characteristic of my invention are set forth with particularity in the appended claims. My invention itself however both as to its organization and method of operation, together with other objects and advantages thereof, will be understood best by reference to the following description taken in connection with the accompanying drawing in which Figs. 1 and 3 diagrammatically illustrate certain characteristics of my system and Figs. 2, 4 and 5 are schematic diagrams of various embodiments of my invention. 15

Referring to Fig. 1, I have illustrated therein by curve A, a characteristic which may be obtained by a loop antenna having a certain amount of vertical effect. If the connections from such an antenna to a receiver be reversed, the field intensity pattern will be transposed so as to produce the antenna characteristic illustrated by the dotted line B. If a radio direction finder utilizing such an antenna and having an output circuit provided with a rectifier and a zero-center indicating instrument were to have the connections between the antenna and receiver, and the connections between the receiver and rectifier reversed simultaneously, a radio transmitter located to the right or left of the point O along the line OC would produce no indication on the zero-center indicating instrument 30 inasmuch as the energy received along the line of intersections OC of the characteristics A and B are equal. If however the radio transmitter is located along any other line such as the lines OR or OL, the energy received by the directive antenna will be unequal, as indicated by these characteristics, since they do not intersect the lines OR or OL at the same point, and hence the output meter would indicate that the transmitter is to the right or left of the line OC. 35 40 45

In accordance with my invention a disclosed in Fig. 2, I have utilized such directive antenna 1 having a certain amount of vertical effect so as to produce a characteristic similar to that disclosed in Fig. 1. The directive antenna 1 is connected to a device 2 which operates to reverse symmetrically and preferably sinusoidally the phase of the energy received by the directive antenna, or in other words, it operates to produce the effect of sinusoidally reversing the connections 50 55

from the antenna 1 to the radio receiver 3, to produce in the output circuit 4 alternating currents of the type disclosed in Fig. 3. When the directive antenna 1 is receiving energy from a station along the line OC, the sinusoidally reversing device 2 operates to produce in the output circuit 4 of the radio receiver 3 a symmetrical alternating current of the form disclosed in Fig. 3 at A. If however the directive antenna is receiving energy from a transmitter to the right of the line OC, as for instance along the line OR, the sinusoidally reversing means operates to produce in the receiver output an alternating current such as illustrated at B in Fig. 3 which is asymmetrical in form due to a certain amount of a second harmonic being introduced into the output of the receiver due to the fact that the energies received in accordance with the patterns A and B are not of equal magnitude. In a similar manner, if the transmitter is located to the left of the line OC, as for instance along the line OL, the alternating currents appearing in the output circuit of the radio receiver will be of the form illustrated at C in Fig. 3. The purpose of producing alternating currents in the output circuit of the radio receiver 3 such as illustrated at A, B and C in Fig. 3 will be apparent later in connection with the detailed description of the elements of the circuit arrangement disclosed in Fig. 2.

The directive loop antenna 1 of Fig. 2 is provided with a capacitor 5 inserted at the midpoint of the antenna. The extremities of the loop antenna adjacent to the capacitor 5 are connected to the terminals of a transformer 6. The outer extremities of the loop antenna 1 are connected to the grids of a pair of electron discharge devices 7 and 8. The anodes of the discharge devices 7 and 8 are connected to a transformer 9 so as to be in push-pull relation, the intermediate point on the primary winding of this transformer being connected to the cathode through a suitable source of anode potential 10. The cathodes of the discharge devices 7 and 8 are connected together and to an intermediate point on the second winding of transformer 6. The other winding of the transformer 6 is connected to a source of low frequency alternating current 11. The source of alternating current 11 connected through the transformer 6 operates to produce upon the grids of the discharge devices 7 and 8, biasing voltages which operate to cause the discharge devices 7 and 8 alternately to become conductive and non-conductive in a sinusoidal manner. Thus at one point in the cycle of the alternating current supplied by the source 11, the discharge device 7 is operative and the discharge device 8 is inoperative. During the next half cycle, the discharge device 8 is operative and the discharge device 7 is inoperative. Thus under one operating condition of the discharge device, energy of a certain phase is transmitted through the transformer 9 to the radio receiver 3 and during the next half cycle, energy of the opposite phase is transmitted to the radio receiver 3. This action of the sinusoidally reversing device 2 in conjunction with the detector of the radio receiver 3 operates to produce in the output circuit 4 alternating currents having a wave form dependent upon the position of the radio transmitter with respect to a direction normal to the null position of the directive antenna. The output circuit includes an impedance element 12 having a hyperbolic resistance-current characteristic. In order to provide a suitable path for alternating currents, and alternating current

components not rectified by the non-linear resistor 12, a by-pass capacitor 14 is connected across the indicating instrument 13. The non-linear resistor 12 is preferably of the type described in United States Patent No. 1,822,742, issued September 8, 1931, to K. B. McEachron, but may be composed of any other material or combination of elements having the desired non-linear resistance-current characteristic.

When asymmetrical currents such as shown in the curves B and C in Fig. 3 are impressed upon the "Thyrite" 12, appreciable rectification of such currents occurs, thereby producing direct current impulses having a polarity dependent upon the asymmetry of the waves impressed. The direct current impulses of different polarity will cause the zero-center indicating instrument 13 to move to the right or left depending upon the polarity of the current, thereby giving an indication as to the location of the radio transmitter with respect to the line OC of the antenna characteristic disclosed in Fig. 1.

In operation, the arrangement disclosed in Fig. 2 when receiving energy from a transmitter normal to the null position of the directive antenna will produce in the output circuit alternating currents of the form disclosed at A in Fig. 3. These alternating currents are not rectified by the non-linear resistor due to its peculiar characteristic which operates only to react to wave forms of asymmetrical shape. Thus the alternating currents of the form A are passed through the non-linear resistor 12 and shunted past the meter 13 by the by-pass capacitor 14. If, however, the direction finder be rotated so that the transmitter is located along the line OR with respect to it, the alternating currents produced in the output circuit 4 of the radio receiver will be of the form B which when acted upon by the non-linear resistor 12 produces direct current impulses which cause the needle of the zero-center indicating instrument 13 to deviate to the right, thereby indicating the direction of the transmitter. Similarly, if the antenna be rotated in the opposite direction so that the transmitter is along a line OL the alternating currents will be in the form shown in Fig. 3 at C which when acted upon by the non-linear resistor 12 produce direct current impulses of opposite polarity, thereby causing the needle of the zero-center indicating instrument 13 to move to the left and indicating the direction of the transmitter received.

Referring to Fig. 4, I have disclosed therein a directive antenna 15 having its midpoint connected to one side of the input to the radio receiver 3. The opposite extremities of the directive antenna are connected through coupling capacitors 16 and 17 to the respective anodes of a pair of electron discharge devices 18 and 19 which have their cathodes connected to the opposite side of the input to the radio receiver 3. The loop antenna 15 may be tuned by a variable capacitor 20. The discharge devices 18 and 19 are of the two-element type, thus constituting simple rectifiers which are caused to become conductive alternately by the impression upon the anodes of the discharge devices of an alternating current potential supplied from a source 21 through the transformer 22, the opposite terminals of the secondary winding of which are connected to the anodes of the respective discharge devices and the midpoint of which is connected to the cathodes of the discharge devices. Thus in operation, alternating current from the source 21 transmitted through the transformer 22 produces a

positive impulse upon the anode of the discharge device 19, while the anode of the discharge device 18 is at negative potential and during the next half-cycle the anode of the discharge device 18 is at positive potential, while the anode of the discharge device 19 is at a negative potential. Thus the discharge devices 18 and 19 operate sinusoidally and alternately to connect the opposite extremities of the loop antenna 15 to the radio receiver 3, thereby producing in the output circuit 4 of the receiver alternating currents similar to those disclosed in Fig. 3 having a wave form dependent upon the position of the transmitter with respect to a direction normal to the null position of the directive antenna. The output circuit 4 of the radio receiver 3 includes the non-linear resistor 12, having a hyperbolic resistance-current characteristic, the zero-center indicating instrument 13 and the by-pass capacitor 14 which operate in the manner described in connection with Fig. 2.

Referring to Fig. 5, I have shown therein a directive loop antenna 23 which has its midpoint effectively grounded through the capacitors 24 and 25. The opposite extremities of the directive antenna 23 are connected to the grids of a pair of discharge devices 26 and 27. These discharge devices 26 and 27 operate as dual purpose tubes to generate audio frequency oscillations and sinusoidally to reverse the phase of the energy received by the antenna 23 as impressed upon the radio receiver 3. The anodes of the discharge devices 26 and 27 are connected through an inductor 28 so as to comprise a push-pull oscillator circuit operating to generate an audio frequency which may be for instance, about 2000 cycles per second. A source of potential 29 connected between an intermediate point on the transformer 28 and the cathodes of the discharge devices 26 and 27 serves as a source of anode current. The inductor 28 is coupled to an inductor 30 the extremities of which are connected to the center of the loop antenna 23 adjacent to the capacitors 24 and 25 respectively. The midpoint of the inductor 30 is connected through a source of potential 31 to the cathodes of the discharge devices and this source of potential operates as a biasing potential for the input grids of the discharge devices 26 and 27. A pair of grids located between the input grids which are connected to the loop antenna and the anodes operate as output electrodes for the discharge devices 26 and 27 and are connected to the extremities of a push-pull output transformer 32 having its midpoint connected to an intermediate point on the source of potential 29. The output circuit of the radio receiver 3 may be provided with a pair of headphones 33 or other translating device and also a filter 35 comprising the inductors 36, 37 and the capacitors 38, 39 and 40. This filter network 35 operates to permit only the frequencies above the frequency of the oscillating circuit 28 to be transmitted through the transformer 41 to the output circuit 4 which includes the non-linear resistor 12, the zero-center meter 13 and the by-pass capacitor 14.

In operation, the discharge devices 26 and 27 through the anode circuit which includes the inductor 28 operate to generate audio frequency oscillations which are transmitted through the inductor 30 to the input electrodes or grids of the discharge devices. These input grids or electrodes are suitably biased by the source of potential 31 so that the discharge devices 26 and 27 operate sinusoidally to reverse the phase of the energy received by the antenna 23 as transmitted

through the transformer 32 to the radio receiver 3. The alternating currents produced in the output circuit of the radio receiver 3 due to the action of the discharge device 26 in sinusoidally reversing the phase of the energy impressed upon the receiver, are similar to those disclosed in Fig. 3 and of a frequency corresponding to the frequency of the oscillations generated in the circuit 28. The network filter 35 prevents any communication frequencies or modulations which may be received by the headphones 33 from reaching the output circuit 4 which includes the impedance element 12 having a hyperbolic resistance-current characteristic. This non-linear resistor 12 in response to asymmetrical currents will produce an indication upon the indicating device 13 as to the relative direction of the transmitter with respect to a direction normal to the null position of the directive antenna.

While in the preferred embodiments disclosed in this application, I have shown and described the means for reversing the input of the antenna to the receiving set as a sinusoidally reversing means, it is to be understood that any other symmetrical reversing means could be used. Such symmetrical reversing means may comprise a mechanical commutator which produces symmetrical or equal periods of the connection of the antenna to the receiver in opposite phase relations. Obviously, of course, the arrangement disclosed has the advantage that no moving parts are utilized, and no contacts such as are incurred by commutators or slip rings are present in the embodiments disclosed. It is therefore only necessary to provide some means for symmetrically reversing the phase of the energy impressed upon the detector by the antenna in order to produce an operative system in accordance with my invention.

While I have shown and described my invention in certain specific embodiments, it will, of course, be understood that I do not wish to be limited thereto, since it is apparent that the principles herein disclosed are susceptible of numerous other applications, and that modifications may be made in the circuit arrangements and in the instrumentalities employed without departing from the spirit and scope of my invention as set forth in the appended claims.

What I claim as new and desire to secure by Letters Patent of the United States is:

1. The combination of a directive antenna for receiving energy from a radio transmitter, a detector, means for symmetrically reversing the phase of the energy impressed upon said detector by said antenna whereby said detector operates to produce alternating currents having an asymmetrical form dependent upon the position of said antenna with respect to said transmitter, and means including an impedance device having a hyperbolic resistance-current characteristic for receiving said alternating currents, said impedance being responsive to asymmetrical currents to produce unidirectional current impulses.

2. The combination of a radio transmitter, a directive antenna having an unbalanced reception characteristic, a translating device connected to said antenna, means for symmetrically reversing the input of said antenna to said translating device thereby producing in the output of said translating device alternating currents having an asymmetrical form dependent upon the position of said antenna with respect to said transmitter, and means having a hyperbolic re-

sistance-current characteristic responsive to asymmetrical alternating currents for translating said asymmetrical alternating currents into unidirectional current impulses having polarities dependent upon the positions of said antenna with respect to said transmitter.

3. The combination of a radio transmitter, a directive antenna having an unbalanced reception characteristic, a translating device connected to said antenna, means for symmetrically reversing the input of said directive antenna to said translating device, said reversing means and said translating device cooperating to produce asymmetrical alternating currents whenever said directive antenna deviates from a direction normal to the direction of the null position of said antenna with respect to said transmitter, and a circuit for receiving said alternating currents including an impedance device having a hyperbolic resistance-current characteristic for translating said asymmetrical currents into unidirectional currents.

4. The combination of a directive antenna for receiving energy from a radio transmitter, said antenna having an unbalanced reception characteristic, a detector for receiving energy from said antenna, means for symmetrically reversing the phase of the energy impressed by said direc-

tive antenna upon said detector, said reversing means cooperating with said detector to produce asymmetrical alternating currents having an asymmetry dependent upon the relation between the direction of the plane of said antenna and the direction of said transmitter, and means for receiving said alternating currents and producing unidirectional currents having a polarity dependent upon the asymmetry of said alternating currents.

5. The combination of a directive antenna for receiving energy from a radio transmitter, said antenna having an unbalanced reception characteristic, a detector for receiving energy from said antenna, means for sinusoidally reversing the phase of the energy impressed by said directive antenna upon said detector, said reversing means cooperating with said detector to produce asymmetrical alternating currents having an asymmetry dependent upon the direction of the plane of said antenna with respect to the direction to said transmitter, and means including an impedance device having a hyperbolic resistance-current characteristic for receiving said alternating currents and producing unidirectional currents having a polarity dependent upon the asymmetry of said alternating currents.

LAURENS A. TAYLOR.
